UNITED STATES PATENT OFFICE

NILS O. LINDSTROM, OF NUTLEY, NEW JERSEY, ASSIGNOR TO A. B. SEE ELEVATOR COMPANY, INC., A CORPORATION OF DELAWARE

ELEVATOR CONTROL DEVICE

Application filed July 13, 1927. Serial No. 205,288.

My invention relates to elevator control devices, and particularly to control devices including automatic means, adapted to manual control, for bringing an elevator car to an accurate stop at a desired floor level. My invention provides a simple, mechanically rugged device for the above purpose, which contains a minimum number of moving parts of the most simple, durable character, and a minimum number of electrical circuits and members.

Elevators are now constructed for operation by electric power, which is controlled, through the agency of a car controller lever, by means of contactors and such like devices, an electrical motor being connected with the winding drums for the actuation thereof, and the operation of the motor, including choice of direction of operation is controlled by appropriate circuits, contacts, and resistances. The simpler systems depend entirely upon the judgment of the operator for the making of accurate stops at the various floor levels, and require either that he develop great skill in moving the control lever at the proper point in the car travel, or that he "inch" the car after making the stop, to level it off with the desired floor. Such manual handling of the car has, however, been found unsatisfactory, because of the fact that it reduces the number of trips which can be made per hour for a given full car speed, because of the delays at each stop. Various attempts have been made to provide automatic means for the making of the various stops, to insure that the car is leveled with the desired floor, including various means for automatic inching of the car. These, however, have been unsatisfactory, because of the complexity of the devices, because of the high cost thereof, and because of the fact that they produce, when so operated, no increase in average speed over that obtainable by ordinary manual operation.

My invention provides a simple, inexpensive device, adapted to be included in the usual elevator control circuits, with a minimum change therein, which functions at the operator's will, to stop the elevator car, automatically and accurately at a desired floor level.

My invention utilizes the well known and long used cam and lever device, previously embodied in shaftway limit stops, in a broadly new combination, and for a broadly new purpose. My invention provides a plurality of pairs of wedge cam members, appropriately positioned within the elevator shaft, in suitable relation with the various floor levels. Upon the elevator car is mounted a device containing mechanical contactor members, magnet members, and cam roller and lever members, adapted to cooperate with the shaftway cam members. The auxiliary device remains inactive until the operator desires to make an automatic stop, whereupon by appropriate means he energizes circuits and a magnetic latch device therein, which brings the lever members into play, whereafter by engagement with the shaftway cams, the contactor members are actuated, and the circuits changed to produce a stop, the actuating cams being so set as to bring the car to rest at the desired point. This may be done in a single step, or may be done in a series of steps, providing for successive degrees of slowing down of the car. The cam and lever members are rugged, durable, well tried pieces of mechanism, having been widely used for limit stops, at top and bottom of the elevator shaftway. The controller members and contacts likewise are old and well known and well developed devices. Similarly the magnetic lock members are simple and rugged. The combination is, however, broadly new, and its function is likewise broadly new, never to my knowledge having been previously so used.

Accordingly, by the device of my invention, I provide a new and useful means whereby a rapid accurate automatic stop is made at a desired floor level, at the operator's will, by a very simple, rugged controlling device, and whereby a proportionately rapid start may thereafter be made by the same devices. My device likewise consists entirely of tried and proven parts, well developed for the purposes intended and of the utmost durability.

Other objects and structural details of my invention will be apparent from the following description when read in connection with the accompanying drawings, wherein:

Fig. 1 is a diagrammatic representation of circuits and apparatus of an embodiment of the device of my invention.

Fig. 2 is a side view of the details of the 5 cam and lever actuating member of the same embodiment of my device.

Fig. 3 is a top plan view of the same device and

Fig. 4 is a side view of the same device 10 enclosed in a suitable protecting case.

Figure 5 is a fragmentary sectional elevation of the controller lever.

Referring to the drawings, I provide, as shown, an elevator car 1 adapted to vertical 15 motion in a shaftway between guides 2. The car 1 is supported by cables 3 passing over sheaves 4 to a counterweight 5, and operated by a motor 6. A car controller 7 is provided, connected by appropriate circuits cooperat- 20 ing with appropriate controller devices, to the motor 6, which circuits will be later described in detail. A cam and lever control-circuit switching device 8 is provided, which may desirably be mounted upon the top of 25 the elevator car, or may be mounted as desired upon other convenient points about the car. The car and motor members of the device of 30 my invention may take any desired suitable form, and may be adapted to operate upon direct current as shown in the embodiment herein disclosed, or may be operated upon alternating current by any of the well known systems, or they may take the form of the so-called "Ward-Leonard" system, or any de- 35 sired combination or modification thereof. The car switch 7 may desirably be of a stand- 40 ard pattern, with the inclusion of the necessary modifications to adapt it to use with the system of my invention.

Combined with these usual elements is a 45 new control-switch member 8 shown in further detail in Figs. 2, 3 and 4. In the construction of this control-switch member a suitable base plate 9 is provided upon which 50 are mounted upright members 10 adapted to the support of pin bearing members 11. Upon the bearings 11 are journalled pairs of magnetic circuit members 12 and 14. These members are adapted to cooperate to form a 55 complete magnetic circuit, but may have their ends separated, producing an air gap m therebetween, as indicated. The ends of the members 12 and 14, at the air gap m , are surrounded by magnetizing coils 15 and 15a 60 which are appropriately mounted upon supporting plate members 16. To the members 14 are attached lever arms 17 having roller members 18 journalled upon the free ends. To the members 12 are attached arm members 19 having quadrant portions 21 upon the free 65 ends thereof. Insulating sectors 22 are suitably attached to the quadrants 21, and suitable sets of contactor segments 24 are attached to the insulating members 22 and by them, 70 insulated from the quadrants 21 and arms 19.

As indicated, the upright members 10 extend to points above the portion supporting the pin bearing 11, and insulating members 25 are attached thereto. Suitable groups 26 of contactor fingers are attached to the insulating members 25, and cooperate with the contactor segments 24.

A cover member 27 is desirably provided, having openings for the passage of the lever members 17, and protecting the magnet and 75 contact structures, as shown in Fig. 4.

Appropriate shaftway cam members 28 are provided as indicated, and attached to the shaftway by appropriate means, which may desirably permit of a limited amount of adjustment. 80

In the preceding description I have indicated as desirable, a construction including two complete sets of magnetic structures, magnet coils, contact sectors, lever arms, etc., 85 as well as pairs of cam members 28. This I find to be a preferred embodiment, because of the lighter service imposed upon the parts, since the respective sets are alternatively active for the stops respectively in an upward 90 or downward direction. My invention is however, not limited to such construction, as the number of parts may be reduced by obvious modifications.

The cams 28 are adapted to be mounted 95 upon the shaftway structure, and to cooperate with the rollers 18 in such way that upon energization of one of the magnet coils 15 or 15a, the members 12 and 14 are drawn and held together by the action of the magnetic 100 flux, and the roller 18 brought into the position-line of the cams 28, so that when it engages therewith, the members 12 and 14 are revolved with respect to the bearing 11, and the position of the contact segments 24, with 105 respect to the contact fingers 26, is changed for the appropriate changing of circuits in the elevator control system. Whenever the magnet 15 or 15a is energized, the members 12 and 14 within the magnetizing coil are held 110 together so as to be movable on their pivot as a single piece, but when the magnet is deenergized gravity causes the member 14 to move into the position shown in Fig. 2.

The device of Figs. 2, 3, and 4 is desirably 115 appropriately mounted upon the top of the elevator car 1, as shown in Fig. 1.

The controller device 7 may desirably take the form indicated in the figures, comprising a lever member 29 having a conducting 120 quadrant 31 which may desirably be insulated therefrom. Groups of contact fingers 32 and 33 are provided cooperating with the sector 31, for the control of appropriate circuits. The lever 29 is provided with an operating handle 34, which is desirably constructed for a sliding movement parallel to the axis 35 upon which the lever 29 is mounted. The handle 34 is secured to the end of a rod 34a which is slidably mounted 125 130

in the lever 29. The rod 34a is provided with a radial projection 34b which is adapted to be received in a groove 29a in the lever and which when out of alignment with the groove 5 holds the handle 34 in the position shown in Figure 5 against the action of a convolute spring 34c which acts against one side of the lever 29 and a flange 34d formed on the rod 34a. The rod 34a is also provided with a 10 pin member 36 which in the position shown in Figure 5 is adapted to engage depressions in a locked plate 37, to prevent accidental movement thereof. When the projection 34b is in position to be received in the groove 29a the pin member 36 on the rod 34a will be advanced to the position shown in broken lines, in which position it is adapted to actuate additional contact members 38 and 39.

A suitable control panel board member 41 20 is provided for cooperation with the motor 6. Upon the panel board 41 are desirably mounted a relay operated contactor 42 for closing circuits for the up (U) motion of the elevator car, and a relay operated contactor 43 for closing circuits for the down (D) motion. An automatic accelerating relay operated contactor 44 is also desirably mounted upon the control board, and also a high-speed field-weakening relay operated 30 contactor 45. Appropriate resistances 46 and 47 are likewise provided, and mounted in suitable places, which may be the back of the panel board or may be other suitable locations.

Appropriate circuits are provided between the various contacts of the controller 7, the automatic stop device 8, the contactors upon the panel board 41 and the motor 6. Power, which in the embodiment chosen for 40 demonstration of the device of my invention, may desirably be direct current, is provided through the leads 48. Connection is made from the positive lead through the wire 49 in the cable 51 to contacts *a* in the controller 7. Connection is also made from the wire 49 to one of each of the pairs of contacts 38 and 39. A wire 52 is led from the contact *b* of the controller 7 to one of the group of brushes 26 in the member 8, indicated at 53. The brush 53 bears upon one 50 of the group of metal segments 24 indicated at 54, which makes contact with a second brush 55 of the group, to which a wire 56 is connected and led to the energizing coil of the contactor 43 for the down motion. A wire 57 connects the coil of the contactor 43 to the negative lead 48 thereby completing the circuit. A wire 58 is also led from the contact *c* in the controller 7 to a brush 59 of 60 the group 26 in the device 8 which bears upon a sector 61 of the group 24. Another brush 62 of the group 26 bears upon the sector 61, and a wire 63 is connected thereto and led to the closing coil of the contactor 42 for the up motion. A wire 64 connects the

coil 42 to the negative lead 48 and completes the circuit. Contacts *d* in the controller 7 are connected together and by a wire 65 are connected to a brush 66 in the device 8, which brush bears upon a sector 67. Another brush 68 bears upon the sector 67 and is connected by a wire 69 to a brush 71 bearing upon the sector 72. Another brush 73 bears upon the sector 72 and is connected by a wire 74 to the opening coil of the high speed contactor 45. A wire 75 connects the same coil to the negative lead 48 and completes the circuit. A wire 76 is led from the second one of the pair of contacts 38 to the coil 15 in the device 8, and the wire 77 is led from the second one of the pair of contacts 39 on the up side to the coil 15a in the device 8. The other terminals of the coils 15 and 15a are connected together and to a wire 78 which connects to the negative lead 48 thereby completing the circuit.

Appropriate limit switches, door safety switches, and other similar safety devices are desirably provided in the device of my invention, but they may take the standard form, well known to those skilled in the art, and accordingly they are not shown in the figures. Likewise the customary electrically operated brake, which may desirably be of the solenoid type is incorporated in the elevator mechanism, for the usual purposes. This also may take the usual form, and accordingly it is not herein described.

In the operation of my device the operator chooses his direction of motion, up or down, and moves the elevator control lever 29 in the appropriate direction by pulling the handle 34 forward to disengage the pin 36 from the latch 37, and swings the lever to carry the sector 31 into engagement with the contacts. If he desires to go downward, he swings the lever to the left, and the sector 31 engages with contacts *a* and *b* of the group 32. Current then flows from the positive lead of the power supply mains 48 through the wire 49, the contact *a*, the contact *b*, the wire 52, the brush 53, sector 54, brush 55, wire 56, through the closing coil of the contactor 43, and the wire 57 back to the negative power supply lead 48. Energization of the contactor 43 closes its contacts and applies power through the leads 81 and 82, and through the resistance 46, to the armature of the motor 6. The field of the motor 6 is continuously energized through the leads 83 and 84. The closure of the contactor 43 and the flow of current through the armature causes the motor to revolve, and the car to move in the appropriate direction. As the motor gains speed, the counter EMF 125 in the armature rises and a rising voltage is imposed upon the closing coil of the contactor 44 through the leads 85 and 86. At a predetermined voltage value the contacts of the contactor 44 close, and the resistance 130

is short circuited in the well known way, whereupon the motor comes up to running speed. Thereafter the operator may swing the lever 29 to the limit of its travel, therefore bringing the sector 31 in contact with the contacts *a*, *b* and *d*. Current then continues to flow in the previously described circuit and also flows from the wire 49 through the contact *a*, the sector 31, the contact *d*, the wire 65 to the brush 66, the sector 67, the brush 68, the wire 69, the brush 71, sector 72, brush 73, and the wire 74 to the coil of the contactor 45. Energization of the coil of this contactor opens its contacts, and inserts the resistance 47 in circuit with the field of the motor 6, thereby weakening the field and speeding up the motor, for the maximum speed.

The movement of the lever 29 and the handle 34 to full speed position, brings the pin 36 of the handle 34 over the contacts 38 on the down side. The operator can then make an automatic stop from the full speed position, by pushing the handle 34 inward. Such movement of the handle causes the pin 36 to close the contacts 38. Current then flows from the wire 49 through the down contacts 38, and the wire 76 to the magnet coil 15, from which it flows through the wire 78 to the negative lead of the supply mains 48. Energization of the coil 15 pulls the members 12 and 14 together, closing the air gap *m*, and bringing the roller 18 into a position to engage with the cam 28. As the elevator continues its travel, the roller 18 engages with the first incline *o* of the cam 28 and is moved outward. The magnetic flux within the members 12 and 14, however, holds them together, and they accordingly swing as a unit under the drive of the cam 28 through the roller 18 and the lever 17 in a manner which is obvious from the construction of the device, and carry with them the sector 21, and its attached contact segments. The movement of the roller along the incline *o* to the first land of the cam moves the sectors but a small amount, sufficient to bring the sector 72 from under the brushes 71 and 73, thereby opening the circuit of the contactor 45, allowing its contacts to close and short circuit the resistance 47, to strengthen the field of the motor 6 and reduce its speed. Thereafter the roller 18 travels along the incline *p* of the cam 28, carrying the sector 19 still further and moving the contact segment 54 away from the brushes 53 and 55 to open the circuit of the contactor coil 43. This opens the armature circuit, and applies the automatic brake in the well known manner, to stop the car.

The stop is thus made under the control of the cam 28 which may be appropriately adjusted so that the stop occurs accurately at the corresponding floor level, thereby producing an accurate, rapid, automatic stop at

the desired floor. The operator may then open the door for the entrance or exit of passengers.

Thereafter without moving the controller lever from the full down position, he may resume travel in a downward direction by pulling the handle 34 outward, thereby opening the down contacts 38, de-energizing the coil 15, releasing the members 12 and 14, and permitting the sector 19 to resume its previous position, closing the circuits between the brushes 53 and 55, and 71 and 73. The completion of the contacts between the brushes 53 and 55 recloses the contactor 43, and supplies current to the motor 6, whereupon it starts, and the automatic accelerating relay 44 operates as before to bring the motor up to speed. Immediately after the closing of the circuit through the brushes 53 and 55, the circuit through the brushes 71 and 73 is also closed, to energize the relay 45, and weaken the field of the motor 6. A rapid start is thus obtained in the desired direction, and the car travels onward. A second stop may be made in a similar fashion, or a stop may be made by the usual movement of the controller handle to the middle position.

It is not necessary that the start be made with the handle in the full travel position after a stop in that position, but the handle may be returned to the neutral position immediately thereafter, and a start in the other direction or in the same direction be made in the same manner as the first start.

A similar sequence of operations occurs for starting in the up direction by movement of the controller lever to the other side. The same movement of the handle is required to release the lever, and a similar energization of similar circuits occurs, for the closure of the contactor 42 for the up motion. The closure of this contactor supplies current to the armature of the motor 6 in the reverse direction, causing the motor to run accordingly. The motor accelerates in an exactly similar manner to running speed, and may be accelerated to full speed by the full throw of the controller lever to engage the contact *d* as before. An automatic stop may similarly be made by closure of the up contact 39 through the agency of the pin 36 attached to the handle 34. A similar set of circuits are brought into play for stopping the car. These circuits being similar to those previously described are readily followed upon the drawings.

A pair of the cam members 28 may be provided at each floor at which it is desired to make automatic stops, including both the top and bottom floors. Likewise the customary safety limit stops may be incorporated in the structure at the top and bottom of the shaft, as an added precautionary measure. It is, of course, not necessary that the cam 28 for stopping during upward travel be included at the bottom of the shaft nor is it necessary

that the cam 28 for downward movement be included at the top of the shaft. At intermediate floors, however, both kinds are required.

5 The device of my invention thus provides a simple, rugged, inexpensive device for automatically stopping an elevator at an accurately predetermined position, at the will of the operator. The disclosure shown is 10 adapted to application to a manually operated elevator. It is, however, equally applicable to fully automatic, or push button control elevators, for the making of more accurate stops at the floor levels. The necessary changes for application in such a device are simple, and will be obvious to one skilled in the art.

15 While I have shown but a single modification of the device of my invention, it is adapted to other modifications therefrom, as previously suggested, and it is desired, therefore, that only such limitations shall be imposed thereon as are required by the prior art or indicated by the appended claims.

20 25 I claim as my invention:

1. In an elevator mechanism, a car controller having running contacts, a hand lever having an auxiliary member, and a stopping contact cooperating with the auxiliary member of the hand lever, and means cooperating with said stopping contact for the automatic stopping of said elevator at a predetermined point, comprising shaftway cams, a cooperating cam lever member, an auxiliary contact device and a magnet cooperating therewith under the control of said stopping contact.

2. An elevator device, comprising an elevator car, winding gear, motor, and control 40 device therefor, said control device comprising a car lever, contacts cooperating therewith, a control switchboard connected thereto, adapted to the control of the movements of said car, and an auxiliary automatic means 45 for effecting a stopping and starting thereof, at the will of the operator, comprising auxiliary contacts cooperating with said controller lever and a circuit changing device connected thereto, and connected between said controller and said switch panel, comprising contactor segments and brushes, a roller lever, a magnet associated therewith and connected to said auxiliary contacts, and cam members attached to the elevator shaftway, and 50 cooperating with said roller lever members.

3. In an elevator control device, a master lever positioned in the car and adapted to the control of the movements thereof, having an auxiliary member adapted to engage a contact when in the full throw position for the automatic stopping thereof, and stopping means comprising cam and lever members, and a magnet under the control of said auxiliary member and associated circuit switch-

50 ing means and controlling said lever members.

4. In an elevator, a shaftway cam, a switch on the car for controlling the stopping thereof, a member movable into position for contacting said cam, and electromagnetic means for moving said member into such position and magnetically uniting it to said switch. 70

5. In an elevator, a shaftway cam, a switch on the car for controlling the stopping thereof, a member movable into position for contacting said cam, and electromagnetic means under control of the operator for moving said member into such position and magnetically uniting it to said switch. 75

6. In an elevator, a shaftway cam, a switch on the car for controlling the stopping thereof, a member movable into position for contacting said cam, and electromagnetic means for moving said member into such position and magnetically uniting it to said switch, 80 said means being deenergized during the running of the car.

7. In an elevator, a manual controller on the car having low and high speed positions, an auxiliary car stopping switch on the car, a shaftway cam, and electromagnetic means controllable by the operator while the controller is in high speed position to cause said cam to operate said auxiliary switch to stop the 90 car. 95

8. In an elevator, a manual controller on the car for closing a circuit to operate the car, an auxiliary switch on the car for opening said circuit, a shaftway cam, and electromagnetic means controllable by the operator while the controller is in running position to cause said cam to operate said auxiliary switch and stop the car. 100

9. In an elevator, a manual controller on the car for closing a circuit to operate the car, an auxiliary switch on the car for opening said circuit, a shaftway cam, and electromagnetic means controllable by the controller handle while the controller is in running position to cause said cam to operate said auxiliary switch and stop the car. 105

10. In an elevator, a manual controller on the car having low and high speed positions, an auxiliary car stopping switch on the car, a shaftway cam, and electromagnetic means controllable by the controller handle while the controller is in high speed position to cause said cam to operate said switch to stop the car. 115

11. In an elevator, a manual controller on the car having low and high speed positions, an auxiliary switch on the car, a shaftway cam, and electromagnetic means controllable by the operator while the controller is in high speed position to cause said cam to operate said auxiliary switch to stop and start the car. 125

12. In an elevator, a manual controller on the car for closing a circuit to operate the car, 130

an auxiliary switch on the car for opening and closing said circuit, a shaftway cam, and electromagnetic means controllable by the operator while the controller is in running position to cause said cam to operate said auxiliary switch to stop and start the car.

5 In witness whereof, I hereunto subscribe my signature.
